UNITED STATES PATENT OFFICE.

IDALYNE M. BEEMER, OF LOS ANGELES, CALIFORNIA.

DESIGN FOR A FLAG, BANNER, PENNANT, SIGN, EMBLEM, OR ARTICLE OF A SIMILAR NATURE.

53,699.

Specification for Design.

Patented Aug. 19, 1919.

Application filed October 21, 1918. Serial No. 259,029. Term of patent 3½ years.

To all whom it may concern:

Be it known that I, IDALYNE M. BEEMER, a citizen of the United States, residing at Los Angeles, county of Los Angeles, State of California, have invented a new, original, and ornamental Design for Flags, Banners, Pennants, Signs, Emblems, or Articles of a Similar Nature, of which the following is a specification, reference being had to the accompanying drawing, forming a part thereof.

The figure is a front elevation of a flag showing my design.

I claim:

The ornamental design for a flag, banner, pennant, sign, emblem or article of a similar nature as shown.

IDALYNE M. BEEMER.
